METHOD AND APPARATUS FOR WARPING
A BEAMTobias Rovas, Cleveland, Ohio, assignor of forty
per cent to Ohio Knitting Mills, Inc., Cleveland,
Ohio, a corporation of Ohio

Application May 1, 1948, Serial No. 24,643

7 Claims. (Cl. 28—54)

1

This invention relates to a method and apparatus for winding yarn or threads on a warp beam used in knitting machines.

In knitting certain articles, such as sweaters, it is desirable to weave the fabric in web form in such manner that one longitudinal half has the pattern reversed with respect to the other half, so that when the finished web is folded longitudinally the patterns will be superimposed upon each other. This will enable two identical panels to be cut simultaneously. Heretofore, the strands have been wound through a guidebar from the bobbin, but when one section has been wound, the guidebar has been rethreaded whenever a reversal of the pattern was desired. Such rethreading operation required considerable time and painstaking effort to assure precise positioning of the threads with respect to each other, particularly where threads of different color have been used in making the pattern.

Another difficulty encountered in the winding of strands onto a beam, or in "warping a beam" as it is called in the trade, has been to make the strands of equal length on the respective sections of the beam. Such difficulty has been augmented by the use of sheets of paper which have been interposed in the material for the purpose of supporting the ends of the adjacent sections. Such sheets have been interposed at intervals of about one inch in depth of yarn on the beam and have overhung the ends of the sections. The introduction of the paper, however, has made it difficult to determine accurately the precise length of threads or strands that are wound onto the beam.

To overcome the foregoing objections, the practice has been to wind strands in a predetermined pattern upon a pilot beam, which is usually about three feet in diameter, and then to rewind from the pilot beam onto the individual warp beams. Each warp beam, when wound, is approximately fifteen inches in diameter, and inasmuch as there are usually five or six beams used on a knitting machine, it is apparent that beams having a size of the pilot beam could not be used within the space limitations of a knitting machine.

An additional objection to the use of a pilot beam is that the rewinding operation from the pilot to the warp beam requires as much as fifty sheets of paper to be interposed between layers, particularly where about four sections are wound

2

onto the beam, and such practice has necessitated not only the expenditure of considerable time during winding, but has introduced a problem of removing the paper from the beams and disposing of it during the unwinding operation.

An object of the present invention is to provide a method and apparatus by means of which the strands may be wound directly from the individual bobbins onto a beam, without necessitating the use of interposed sheets of paper and without wasting space on the beam between adjacent sections.

A further object of the invention is to utilize a method and apparatus by means of which strands of different color may be wound onto the beam directly from the bobbins in one prearranged sequence, until the desired length has been wound thereon, and thereupon the same sequence may be wound in another section, but with the order of the strands reversed, with respect to their position on the first section. The invention contemplates an arrangement by means of which the reversal may be accomplished without rethreading the threads through a guidebar or cone as has heretofore been the practice.

An advantage of the present invention is that approximately twice as much yarn can be wound onto a beam, thus enabling a knitting machine to obtain twice the production for one threading of the machine; that the necessity for interposing sheets of paper between layers of yarn on the beam has been eliminated, and that considerable wastage has been saved, because on every threading operation there has been a wastage of one or more feet on each strand. This item is an appreciable factor because, generally, there are about one thousand threads wound on each beam.

Referring to the drawings, Fig. 1 is a side elevation of the device embodying my invention and illustrating the winding of a beam; Fig. 2 is a perspective view illustrating the winding of a section on a beam on which two sections have previously been wound; Fig. 3 is a perspective view illustrating the manner of manipulating the guidebar to effect a reversal of thread position; Fig. 4 is a perspective view showing the position of the threads reversed with respect to that illustrated in Fig. 2; Fig. 5 is a side elevation of a portion of the apertured bar used in connection with the invention; Fig. 6 is a side elevation

through a portion of the supporting structure for the guidebars, and showing a portion of it in section; Fig. 7 is a side view of a spacing device that is used in connection with the operation of the present invention; Fig. 8 is a section taken on a plane indicated by the line 8-8 in Fig. 7; Fig. 9 is an exploded side elevation illustrating the separability of the parts of the collar illustrated in Fig. 7; Fig. 10 is a perspective view illustrating the manner in which the collar may be assembled onto the beam; Fig. 11 is a longitudinal section on a scale larger than that used in Fig. 7 and shows the locking device by means of which the collar sections can be held in assembled relationship.

In Fig. 1 I have shown my invention in connection with a stand 10 having bobbins 11 mounted thereon with strands of yarn or thread 12 extending from the respective bobbins to a gathering device, from which they are wound on the beam 15. The beam is journaled in upright members 16 of a frame 17 and is adapted to be rotated by an electric motor 18 through a belt connection 19. The bobbins are shown as having their respective axes disposed in a vertical plane but such showing is only diagrammatic, it being understood that the bobbins may be mounted, if desired, with their axes in a horizontal plane, whereby the threads can be withdrawn from the bobbin in a movement generally axially of the bobbin.

The gathering device forming the subject matter of the present invention includes a vertically extending apertured bar 20 through which the strands pass, and a horizontally disposed apertured bar 21 through which the strands also pass in their travel from the bobbins to the beam. The device also includes a roll 22 around which the strands pass in their travel from the bar 21 to the beam, as is shown particularly in Fig. 2. The bars 20 and 21 and the roll 22 are supported upon a carriage, indicated in general at 23 which is slidably mounted in guideways on beams 24, 25 which extend longitudinally of the frame. The purpose of the carriage is to permit the strands to be wound onto the beam in one section, and then shifted as a unit to permit the winding of the threads, either in the same or in reverse pattern, on another section of the beam.

The vertically disposed bar 20 is shown as being supported at its lower end in a curved guideway 27 on the carriage bed, and as being adapted to be clamped in any desired position by a thumb nut 28 which engages a threaded stud 29 on the bar 20. Thus, the bar 20 may be positioned either close to or remote from the beam, or at an angle to the bar 21 in accordance with the expediency of the particular section that is being wound on the beam.

The horizontal bar 21 is preferably provided adjacent its mid-portion with studs 30 and 31 which extend from the top and bottom edges respectively of the bar, and which are substantially the same in length and in diameter. In use, one stud is adapted to extend into and to be swivelly mounted within a socket 32 in a standard 33 which is rigidly supported upon the bed of the carriage 23, as is shown in Fig. 2. Thus, when the stud 30 for example is disposed within the socket 32, the stud 31 is uppermost and is supported in a socket 34, which is disposed in the lower end of a strut 35. The upper end of the strut has a socket which receives the upper end of the bar 20 and is provided with a thumb nut 36 for clamping the stud to the bar. Each of the bars 20 and

21 has a series of spaced apertures 37 which may be of different size and arranged in spaced rows, as is shown for example in Fig. 5.

The roll 22 is journaled in the carriage and has an abrasive surface so as to avoid slippage between it and the strands. Thus, by connecting a counter 40 to the shaft, the number of revolutions of the shaft and, therefore, the length of the yarn wound onto the beam, can be accurately determined. In this way, the length of yarn on the respective sections wound onto the beam can be readily controlled.

A further feature of the present invention is the provision of relatively thin detachable collars which are adapted to be positioned between sections upon the roll, and which function to support the adjacent end portions of the sections as the yarn is wound onto the beam. The outermost ends are adapted to be supported by flanges 47 which are held in place by set screws 48. Preferably, each collar embodies a thimble 45 which has an opening 46 to receive the beam. Each thimble has an annular groove 49 therein for receiving a pair of semi-circular sections 50 and 51. Each section has a semi-circular notch 52 for receiving the thimble, and each embodies a relatively thin plate so as to occupy as small a space as possible between the sections of yarn wound onto the beam.

The collar members are adapted to be locked together so as to form a partition between adjacent sections. A preferred form of locking device includes a pin 53 which is carried on one member and is adapted to coact with a latch 54 on the adjacent member. Each latch is pivoted, as at 55, and is shaped at its free end to engage a notch 56 in the coacting member. The pin is slidably mounted within a cylinder 57 and is urged outwardly to a position overhanging the notch by a spring 58. The end 59 of the pin is then adapted to engage the latch so as to clamp the coacting members together. The opposite end of the pin projects through the other end of the cylinder and terminates in a head 60 by means of which the pin can be withdrawn manually to permit unlatching of the collar.

Fig. 10 shows one collar, indicated at 61, as being fastened to the beam 15 and another collar, indicated at 62, as being attached to the beam. As soon as the two sections of the collar are brought together around the thimble, the latches are moved inwardly about their respective pivots until the ends thereof enter the coacting notches in the companion section. During such movement, the adjacent pins are withdrawn manually to admit the latch ends into their respective notches, and then the pins are released, at which time they project over the latches, as shown particularly in Fig. 7.

In operation, the strands are led from the respective bobbins and threaded through the apertures in the vertical bar 20, thence through the apertures in the horizontal bar 21, thence past beneath the roll 22 and onto the beam. In Fig. 2, the sections designated 63 and 64 have been wound with the pattern in the same sequence, that is, the lines 65 and 66 in each section designate strands of yarn of a color different from that in the remaining portion of the section. The section 67 being wound in Fig. 2, however, is intermediate those designated 63, 64 and has the pattern reversed with respect to such sections, as indicated by the lines 65A and 66A on the intermediate section. To effect such reversal of pattern, the strut 35 is removed, the bar 21 is lifted

out of the socket 32, turned in a vertical plane through an angle of 180°, repositioned on the standard 33, and supported by the replaced strut 35. The manner of accomplishing such reversal is illustrated in Fig. 3 and the position of reversal from that of Fig. 2 is illustrated in Fig. 4. Thus, the pattern of strands wound onto the beam is reversed without necessitating rethreading of the bar. The winding operation is then continued until the number of turns recorded on the counter 40 corresponds to the number used for winding the preceding section, at which time the winding is terminated, the threads are severed between the roll 22 and the beam, the carriage 23 is shifted to the far end of the frame 17 and the strands are attached to the end section 70 of the beam. Thus, in the illustration of Fig. 2, the intermediate section 57 and the end section 70 will be wound in the same pattern, which is reversed to that of the sections 63 and 64.

At the completion of the winding operation, the beam is removed from the machine and is placed upon the knitting machine where, in conjunction with other beams, the threads are brought out and passed through the needles and the knitting operation is started.

Before the knitting operation is started, I may, if desired, move the collar sections from the beam, except the end flanges 47, at which time the wound sections support each other, due to the relative thinness of the material which formed the collar sections. In practice, such plates are approximately one-eighth of an inch in thickness and are, therefore, sufficiently thin to preclude the possibility of the end turns of yarn becoming tangled or fouled on the beam.

I have found that, in operation, the necessity for interposed sheets of paper has been eliminated, and that, because of such elimination, sections can be wound tighter. As a final result, the beams may be wound to contain substantially twice as much yarn as heretofore. In this way, each knitting machine may be operated for substantially twice the length of time for any given threading of the machine. This is an important factor in the economy of operation, because of the time required to thread the needles and to set the beams upon the machine.

I claim:

1. A method of warping a beam for use on a knitting machine comprising, holding strands in spaced relationship in a vertical plane as they are withdrawn from individual bobbins, leading the strands through a guide member disposed in a horizontal plane, passing the strands around an abrasive roll and then onto a warp beam, winding the beam to a predetermined depth, severing the strands between the abrasive roll and beam, moving the vertical and horizontal guides as a unit axially of the beam to a new section on the beam, turning the horizontal guide through 180° in a vertical plane, so as to reverse the position of the strands on the new section of the beam with respect to that previously wound, and then repeating the winding operation on the new section.

2. A method of warping a beam for use on a knitting machine comprising, passing strands through a vertically disposed guidebar in spaced relation from individual bobbins, then passing strands through a horizontally disposed guidebar, supporting the two guidebars for movement with respect to each other and as a unit axially with respect to the beam, thence passing the strands onto the beam, rotating the beam until

strands of a predetermined length are wound thereon, severing the strands, moving the guidebars as a unit, to a new section of the beam while the strands are threaded therethrough adjusting the guidebars with respect to each other and the beam and repeating the winding operation on the new section.

3. A method of warping a beam for use on a knitting machine comprising, taking strands from individual bobbins, passing the strands through apertures in a vertically disposed guide member, then passing the strands through apertures in a horizontally disposed guide member, supporting the guide members for movement as a unit axially of the beam, winding one section of the beam to a predetermined depth, severing the strands at the completion of the winding operation without removing any of them from the apertures in the guide members, moving the guide members as a unit together with the strands axially of the beam to a new section, reversing the position of the strands on the new section with respect to that previously wound by inverting the horizontal guide member without removing the strands therefrom, and then repeating the winding action on a new section of the beam.

4. An apparatus for warping a beam comprising a frame having a beam journaled thereon, means for rotating the beam, a carriage mounted on the frame for movement axially of the beam, a vertically disposed guidebar on the carriage and a horizontally disposed guidebar mounted on the carriage, said carriage having means for adjusting the guidebars with respect to each other and the beam each of said guidebars having apertures therein adapted to receive strands of yarn, and the carriage also having a guide roll around which the strands are adapted to pass in their path of travel from the guidebars onto the beam.

5. An apparatus for warping a beam for use on a knitting machine, comprising a frame adapted to support a beam, means for rotating the beam, a member slidably mounted on the frame in a direction axially of the beam, said member having a vertically disposed guidebar and a horizontally disposed guidebar adjustably carried thereby, each of said bars having apertures therein adapted to receive strands that are to be wound onto the beam, means for supporting the horizontally disposed guidebar in either upright or inverted position without requiring the strands to be removed from the apertures therein, whereby one section of the beam may be wound with the strands in one position and another section 55 may be wound with the strands in reverse position.

6. An apparatus for warping a beam for use on a knitting machine comprising, a frame, a warp beam journaled thereon, means for rotating the beam, a carriage mounted on the frame for movement in a direction axially of the beam and having a curved guideway therein, a vertically disposed guidebar mounted for adjustment in said curved guideway, a standard carried by the carriage, a roll journaled in the carriage between the standard and the beam, a horizontally disposed guidebar swivelly mounted in the standard and adapted to be positioned either in upright or inverted position upon the standard, and each of the guidebars having apertures therein for receiving strands.

7. A device for warping a beam for use on a knitting machine comprising, a frame, a warp beam journaled thereon, means for rotating the beam, means for guiding strands of yarn in a

vertical plane, other means for guiding such strands in a horizontal plane, an abrasive roller interposed between the last-named means and the beam around which the strands are adapted to be passed, and means for supporting the horizontally disposed guide member either in an upright or inverted position, whereby the position of the strands wound onto the beam may be reversed without removing the thread from the guiding members.
